UNITED STATES PATENT OFFICE.

JESSE D. TUCKER, OF SACRAMENTO, CALIFORNIA, ASSIGNOR TO TUCKER BROTHERS MANUFACTURING COMPANY, OF SACRAMENTO, CALIFORNIA, A CORPORATION.

SPOKE-TIGHTENING SHIM DRIFT.

Application filed July 19, 1922. Serial No. 576,153.

To all whom it may concern:

Be it known that I, JESSE D. TUCKER, a citizen of the United States, residing at Sacramento, county of Sacramento, State of California, have invented certain new and useful Improvements in Spoke-Tightening Shim Drifts; and I do declare the following to be a full, clear, and exact description of the same, reference being had to the accompanying drawings, and to the characters of reference marked thereon, which form a part of this application.

This invention relates to a tool to be used in connection with the placing of the spoke-tightening shims or washers insertable between the felly and spokes of a wooden wheel, such shims being preferably of the type shown in my Patent No. 1,411,391, dated April 4th, 1922.

20 The principal object of my invention is to provide a tool to engage the shim, and by means of which said shim may be quickly and easily driven into position, with a minimum of manual handling on the shim on the part of the operator.

A further object of the invention is to produce a simple and inexpensive device and yet one which will be exceedingly effective for the purposes for which it is designed.

30 These objects I accomplish by means of such structure and relative arrangement of parts as will fully appear by a perusal of the following specification and claims.

In the drawings similar characters of reference indicate corresponding parts in the several views:

Fig. 1 is a perspective view of the improved form of the drift, showing the same engaged with a shim.

40 Figs. 2, 3, and 4 are similar views of modified forms of the shim drift.

Referring now more particularly to the characters of reference on the drawings, the numeral 1 denotes the shank of the tool, of circular or polygonal cross section as may be desired, which is flattened and widened on one end as at 2. The outer edge or face of this flat portion, which lies substantially in a plane at right angles to the shank, is curved concavely as at 3 on a radius equal to that of the shim 4 to be engaged.

The foregoing arrangement and general design is common to all the forms of the device shown.

55 In the type shown in Fig. 1, the portion

2 has a right-angle and raised step or ledge 5, set back from the edge 3 a certain distance, the face of which is curved the same as the outer face 3.

The type in Fig. 2 also has a similarly disposed and curved ledge or shoulder 5^a, but the face of this ledge is cut at an acute angle with the portion projecting therebeyond, as shown at 6, and so as to make a V with said portion.

With these two types, in the initial setting of the shim, the ledge is engaged with the periphery of the shim, the tool being held in alignment and engagement therewith by reason of the projecting portion of the end 2 therebeyond, the engagement thus had being somewhat firmer with the type shown in Fig. 2 than with that shown in Fig. 1, owing to the wedging of the shim-edge into the angle formed between the ledge 5^a and the outer end of the tool. When the shim has been driven in a certain distance, the outer edge 3 is engaged with the shim to complete the operation, this edge being but little if any thicker than the shim itself, as is necessary; since when the shim is definitely located the rim thereof is aligned with the periphery of its spoke and overhung by the felly.

In the type shown in Fig. 3, the ledge is omitted, and the end is formed as a single and relatively thin curved-edge portion 7, said edge being straight and at right angles to the axial plane of the tool.

In Fig. 4, the single-thickness end is maintained, but the transverse edge thereof is formed as an angled or circular groove as shown at 8, the latter form of course giving a better engagement with the shim than the straight edged type.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A drift for driving spoke tightening

shims comprising a shank having a relatively thin flattened end whose outer edge extends transversely of the shank, said edge being concavely curved on a radius substantially the same as that of a shim to be engaged thereby and having substantially the same thickness.

2. A drift for driving spoke tightening shims comprising a shank having a flattened end whose outer edge extends transversely of the shank, said edge being concavely curved on a radius substantially the same as that of a shim to be engaged thereby and having substantially the same thickness, and a ledge upstanding from said flattened end a certain distance from the outer edge thereof, said ledge having the same curvature and in the same direction as said outer edge and similarly disposed relative to the shank.

3. A drift for driving spoke tightening shims comprising a shank having a flattened

end whose outer edge extends transversely of the shank, and a ledge upstanding from said flattened end a certain distance from said outer edge having a similar shape as said edge and being similarly disposed relative to the shank.

4. A drift for driving spoke tightening shims comprising a shank having a flattened end whose outer edge extends transversely of the shank, and a ledge upstanding from said flattened end a certain distance from said outer edge having a similar shape as said edge and being similarly disposed relative to the shank, the heights of said end edge and ledge being substantially equal to the thickness of a shim to be engaged thereby.

In testimony whereof I affix my signature.

JESSE D. TUCKER.
